11 Claims. (Cl. 200—144)

My invention relates to circuit breakers, and more particularly to circuit breaker arc chutes having a novel two-piece arc plate construction.

Circuit breakers presently in use are designed to include arc chutes to aid in the rapid extinguishment of an arc which is formed during the tripping operation. Since circuit breakers are tripped to interrupt current of relatively high magnitude, the arc current created as a result of the tripping operation has the same magnitude as the fault current.

The high magnitude arc current created during the tripping operation causes the gases present in the arc chute to be rapidly heated and ionized. The rapidly expanding gases place severe stress on the arc chute and on its associated elements, mainly the arc plates. This explosion which accompanies the tripping operation is the most significant factor to be considered in the design of the arc chute and its arc plates.

The arc chutes of the prior art contain a plurality of spaced parallel arc plates which are interposed between a pair of arc runners contained in the arc chute. The arc plates are formed of insulating or non-conductive material. The arc plates create a tortuous path for the electric arc as it travels upward along the arc runners. The lower portion of each arc plate contains an elongated slot which tapers inward to form an inverted V-shaped notch. The region bounded by the slots permit the hot ionized gases to rise rapidly above the separating contacts and the lower portions of the arc runners thereby preventing a restrike or flashover between the contacts and between the lower portions (arc horns) of the arc runners. Since the region bounded by the inverted V-shaped slots is the path of least resistance in the arc chute, the arc will confine itself to this region when it is first transferred to the arc runners.

In order to create a more tortuous path for the arc when the arc is contained in the region bounded by the arc plate slots, the arc plates have been designed so that the vertex of the V-shaped slot lies to the right of the arc plate longitudinal axis. The arc plates are then stacked in the arc chute in a staggered fashion so that the vertices of alternate arc plates lie to the right of the arc plate longitudinal axis and the vertices of the remaining arc plate slots lie to the left of the arc plate longitudinal axis. This staggered design causes the upward moving arc to be elongated in the horizontal plane as it travels through the region bounded by the arc plate slots.

Since the rapid extinguishment of the arc is of the utmost importance, it is desirable to elongate the arc as much as possible when it lies in the region of the arc plate slots. One manner of doing this is to taper the lower portion of the arc plate and alternate the tapered edges of adjacent arc plates in the arc chute. This design will give the greatest possible horizontal elongation of the arc when the arc is in the region bounded by the tapered edges. The stacking of arc plates having this configuration however, must be done in such a manner as to prevent any sidewise movement of the arc plates due to the explosion which takes place during the tripping operation. One method of securing the arc plates in the arc chute is to form a plurality of slots along the inner-50 faces of the arc chute into which the arc plates may be

2

inserted. Another method is to form flanges along the lengthwise edges of the arc plates which serve to space the arc plates from one another. These methods, however, increase the time and complexity of the manufacturing operations. In addition, spacing means of this type are non-resilient, and, therefore, do not allow for warpage and camber of the arc plates resulting in both a high reject rate of the arc plates and an increase in arc plate breakage.

To overcome these disadvantages, the prior art has employed resilient spacing means between adjacent arc plates which allow for warpage and camber, and also acts as a shock-absorbent material during the explosion resulting from the tripping operation. The resilient material absorbs the arc-forming shock forces, and thereby diverts these forces from the arc plates, thus preventing the plates from being cracked or broken. The resilient spacing means also forms an excellent seal between adjacent arc plates to prevent ionized gases from leaking out past the sides of the arc plates and shorting out parts of the arc chute which would result in failure of the chute.

One type of resilient means presently in use is a resilient material in rope or cord form which is placed on opposite sides of alternate arc plates immediately adjacent the arc plate edges. The arc plates not having the resilient rope along their edges are interspersed between those arc plates having the resilient rope along their edges. By utilizing the resilient rope in this manner, the rope need only be applied to approximately one-half of the arc plates for each arc chute.

The parallel arc plate stack is then partially compressed and placed in an arc chute shell. Designing arc chutes in this manner results in a decrease in the time and complexity of fabrication.

This simplified spacing means, however, may not be employed with arc plates having tapered edges, but is limited to arc plates having inverted V-shaped slots, since arc plates having tapered edges cannot be properly supported by the resilient rope means.

The arc plate design of my invention consists of a two-piece arc plate. One of the two pieces is similar in design to arc plates having a tapered edge in the lower portion of the arc plate. The other member is designed so that its height is slightly less than the upper end of the taper. A resilient material in rope form is placed on opposite faces of approximately one-half of the arc plates immediately adjacent each edge. The two-piece arc plates which are not bound by the resilient rope are interspersed between the arc plates bound by the resilient rope in a staggered fashion so that the tapered edges of adjacent arc plates are now arranged in alternate fashion. The subassembly is then coated on both sides with an epoxy cement and then cured to form a rigid unitary subassembly. The top and bottom of the subassembly may then be trimmed to the proper height and also to create a uniform, even surface across the top and bottom. The shorter pieces of each two-piece arc plate act as spacers for the arc plates on either side of it, thereby providing adequate strength to prevent unnecessary sidewise movement and subsequent breakage which may result from the explosion accompanying the tripping operation. It can, therefore, be seen that this design permits the use of arc plates which create the greatest possible horizontal elongation of the arc in combination with resilient rope spacing means.

It is, therefore, one object of my invention to provide a novel arc plate configuration utilizing resilient spacing means.

Another object of my invention is to provide a novel two-piece arc plate.

Another object of my invention is to provide a novel stacked arc plate configuration having resilient spacing means.

These and other objects of my invention will become apparent after reading the following description in connection with the drawings, in which:

FIGURE 1 is a side plan view of my novel two-piece arc plate.

FIGURE 2 is an end view of the arc plate shown in FIGURE 1.

FIGURE 2a is an end view of the arc plate of FIGURE 1 showing the manner in which the top and bottom edges of the arc plate are trimmed.

FIGURES 3 and 3a show two different manners in which the novel two-piece arc plates may be stacked.

FIGURE 4 is a perspective view showing a stacked assembly of arc plates of the type shown in FIGURES 1 and 2.

FIGURE 5 is a view of the arc plate assembly of FIGURE 4 taken along phantom line A—A¹ of FIGURE 4.

FIGURES 6 and 6a are side and end views respectively of prior art arc plates.

Referring now to the drawings, FIGURE 1 shows the novel arc plate of my invention which is comprised of interrupting member 11 and spacing member 12. The lower portion of interrupting member 11 has a tapered lower edge 13. Spacing member 12 has a tapered edge 14 which cooperates with tapered edge 13 of interrupting member 11 to form a slot 16. The upper end 17 of slot 16 lies to the left of the longitudinal axis shown by phantom line 15. The height of spacer member 12 is slightly less than the height of tapered edge 13 of interrupter member 11, forming a gap 18. Interrupter member 11 and spacer member 12 may be formed from the same sheet of insulating material for the cost of the arc plate alone, enabling the two-piece arc plate 10 to be manufactured at no greater expense than slotted one-piece arc plates of the prior art. Resilient inorganic cord 19 is secured to the opposite edges of two-piece arc plate 10 in any suitable manner (see FIGURE 2).

One method of arc plate stacking is shown in FIGURE 3. It can be seen that resilient cord 19 need only be secured to alternate arc plates 11a, the remaining arc plates 11b being interspersed between the arc plates 11a having the resilient cord 19 secured thereto. It should be noted that the slots 16 (see FIGURE 1) in arc plates 11a have their vertices 17 to the left of center line 25, while the slots 16 in arc plates 11b have their vertices lying to the right of center line 25 for a reason to be more fully described.

Another manner of applying resilient cord 19 to arc plates 10 is shown in FIGURE 3a. In this embodiment, resilient cord 19 is secured to only one edge of each arc plate 11a and 11b. The arc plates 11a and 11b are then stacked so that adjacent plates have resilient cord 19 secured to opposite edges. The slots 16 of arc plates 11 are arranged in the same manner as set forth in the description of FIGURE 3.

When the desired number of arc plates have been properly stacked, as shown in FIGURE 4, the sides 26 of the arc plate assembly are coated with an epoxy cement to form a rigid unitary assembly. The upper 27 and lower 28 edges are then trimmed, making each such assembly of uniform height and also giving a uniform, even surface across the top and bottom of the assembly. This is done by removing the upper 19a and lower 19b loops of resilient cord 19 (see FIGURE 2a). Assembly of the arc plates 10 in this manner permits the unitary stacked arc plate assembly to be inserted into the arc chute shell in a relatively simple manner.

The importance of spacer member 12 shown in FIGURE 1 can be seen from consideration of the arc plate configuration shown in FIGURES 6 and 6a. The arc plates 30 and 31 have tapered edges 30a and 31a respec-

tively, this design being well known in the prior art. Resilient cords 29 and 29a are secured to the opposite sides of arc plate 30 immediately adjacent each edge. Due to the taper 30a of arc plate 30 resilient cord 29a extends down only as far as the beginning 32 of taper 30a.

As can be seen in FIGURE 6a, arc plates 31 which are positioned on opposite sides of arc plate 30 are not properly supported and spaced by resilient cord 29a for the portion 32 of their entire height. This lack of proper support and spacing results in the breakage of portions 32 of arc plates 31 due to the severe impact which they are exposed to by the explosion accompanying the tripping operation of the associated circuit breaker (not shown). It can thus be seen that arc plates having the configuration shown in FIGURES 6 and 6a may not successfully be employed in the assembly shown in FIGURE 4. By utilizing spacer member 12, however, the necessary support is successfully obtained.

The operation of the arc chute is as follows: When the cooperating contacts (not shown) are separated in response to a fault current condition, an arc is drawn between the contacts. The arc is urged upward by either magnetic or pneumatic means, causing the arc drawn between the cooperating contacts to transfer to the arc runners 20 (see FIGURE 5) located at opposite ends of the arc chute. At this instant, the arc is in position B as shown in FIGURE 1. The arc is urged upward through the arc plates 10 which cause the arc to assume a horizontal zigzag path due to the alternate arrangement of the arc plate slots 16. The arc remains in the region of the slots 16, since the area bounded by the slots offers the least resistance to the arc. As the arc moves still further through the arc chute, it assumes the position of gap 18. FIGURE 5 shows the configuration of the arc B at this instant. It can be seen that the arc B assumes a zigzag configuration due to slots 16 in the two-piece arc plates 10. Since the gaps 18 are located at the extreme edges of the arc plate assembly, this configuration affords the greatest possible horizontal elongation of the arc when the arc reaches the level of gap 18.

It can, therefore, be seen that I have provided an arc plate assembly having a novel two-piece arc plate which retains all of the advantages of the one-piece arc plates of the prior art, as shown in FIGURE 6, while the two-piece arc plate configuration permits the use of resilient cord spacer means which have advantageous shock absorbing qualities.

In the foregoing, I have described my invention only in connection with preferred embodiments thereof. Many variations and modifications of the principles of my invention within the scope of the description herein are obvious. Accordingly, I prefer to be bound not by the specific disclosure herein, but only by the appending claims.

I claim:

1. An arc plate assembly for a circuit breaker comprising a plurality of two-piece arc plates, the members comprising each of said two-piece arc plates being coplanar, resilient cord means secured to said arc plates for positioning and securing said arc plates in a spaced parallel arrangement; each of said two piece arc plates being adapted to form a notch therebetween for guiding and elongating an electric current arc to facilitate extinguishment thereof, said resilient cord means being adapted to act as a shock absorber to reduce the impact imparted to the arc plate assembly due to a circuit breaker tripping operation, said resilient cord being formed of an inorganic non-conductive material.

2. An arc plate assembly for a circuit breaker comprising a plurality of two-piece arc plates, the members comprising each of said two-piece arc plates being coplanar, resilient cord means secured to said arc plates for positioning and securing said arc plates in a spaced parallel arrangement, said resilient cord means being adapted to act as a shock absorber to reduce the impact imparted to

the arc plate assembly due to a circuit breaker tripping operation, said arc plate assembly being treated with an epoxy cement to form a rigid unitary assembly.

3. An arc plate assembly comprising a plurality of two-piece arc plates, the members comprising each of said two-piece arc plates being coplanar, resilient cord means secured to approximately one-half of said arc plates for positioning and securing said arc plates in a spaced parallel arrangement, said resilient cord means having a shock absorbing characteristic to absorb the impact imparted to said arc plates due to a circuit breaker tripping operation; each of said two piece arc plates being adapted to form a notch therebetween for guiding and elongating an electric current arc to facilitate extinguishment thereof.

4. An arc plate assembly comprising a plurality of two-piece arc plates, the members comprising each of said two-piece arc plates being coplanar, resilient cord means for positioning and securing said arc plates in a spaced parallel arrangement, said resilient cord means being secured to the opposite faces of alternate arc plates immediately adjacent the edges to provide proper spacing for all of said arc plates, an epoxy cement for bonding said assembly, said cement being applied to opposite sides of said assembly to provide a rigid unitary structure.

5. An arc plate assembly comprising a plurality of two-piece arc plates, the members comprising each of said two-piece arc plates being coplanar, resilient cord means for positioning and securing said arc plates in a spaced parallel arrangement, said cord means being secured to alternate arc plates adjacent one edge of said alternate arc plates and being secured to the remaining arc plates adjacent the edge opposite the said one edge to provide proper spacing for all of said arc plates; each of said two piece arc plates being adapted to form a notch therebetween for guiding and elongating an electric current arc to facilitate extinguishment thereof.

6. An arc plate assembly for a circuit breaker comprising a plurality of arc plates, each of said arc plates including a first and second member, said first member being tapered along its lower portion, said second member being positioned with respect to said first member to form an inverted U-shaped slot between one edge of said second member and the tapered edge of said first member, the vertex of said slot being offset from the longitudinal axis of said arc plate, said first and second members being coplanar, resilient cord means, said resilient cord means being secured to alternate arc plates adjacent one edge and being secured to the remaining arc plates adjacent the edge opposite the said one edge to provide proper spacing for all of said arc plates.

7. An arc plate assembly for a circuit breaker comprising a plurality of arc plates, each of said arc plates including a first and second member, said first member being tapered along its lower portion, said second member being positioned with respect to said first member to form an inverted U-shaped slot between one edge of said second member and the tapered edge of said first member, the vertex of said slot being offset from the longitudinal axis of said arc plate, said first and second members being coplanar, said cord means being secured to alternate arc plates adjacent one edge and being secured to the remaining arc plates adjacent the edge opposite the said one edge

to provide proper spacing for all of said arc plates, said resilient cord means having a shock absorbent characteristic to absorb the impact imparted to said arc plates caused by a circuit breaker tripping operation to prevent breakage of said arc plates.

8. An arc plate assembly for a circuit breaker comprising a plurality of arc plates, each of said arc plates including a first and second member, said first member being tapered along its lower portion, said second member being positioned with respect to said first member to form an inverted V-shaped slot, the vertex of said slot being offset from the longitudinal axis of said arc plate, the height of said second member being slightly less than the height of said tapered edge to form a gap along the edge defined by said first and second members to provide for maximum horizontal elongation of an arc formed during a circuit breaker tripping operation, said first and second members being coplanar, resilient cord means for positioning and securing said arc plates in a spaced parallel arrangement, said cord means being secured to the opposite edges alternate arc plates to provide proper spacing for all of said arc plates.

9. An arc plate arrangement comprising a two-piece arc plate including first and second arc plate members, each of said members being formed of the same material, said first and second members being positioned coplanar to each other, said first member being tapered towards its upper edge, said second member being tapered towards its lower edge, the tapered sides of said first and second members being positioned adjacent one another to form an inverted slot between said first and second members.

10. An arc plate arrangement comprising a two-piece arc plate including first and second arc plate members, each of said members being formed of the same material, said first and second members being positioned coplanar to each other, said first member being tapered towards its upper edge, said second member being tapered towards its lower edge, the tapered sides of said first and second members being positioned adjacent one another to form an inverted slot between said first and second members, said inverted slot being offset from the central axis of said second arc plate member.

11. An arc plate arrangement comprising a two-piece arc plate including first and second arc plate members, each of said members being formed of the same material, said first and second members being positioned coplanar to each other, said first member being tapered towards its upper edge, said second member being tapered towards its lower edge, the tapered sides of said first and second members being positioned adjacent one another to form an inverted slot between said first and second members, bonding means for sealing said first member to said second member, said bonding means being further adapted to space said two-piece arc plate from adjacent arc plates.
